UNITED STATES PATENT OFFICE

HENRY E. MUCHNIC, OF ATCHISON, KANSAS, ASSIGNOR TO THE LOCOMOTIVE FINISHED MATERIAL COMPANY, OF ATCHISON, KANSAS, A CORPORATION OF KANSAS

PAVING TILE

Application filed May 7, 1931. Serial No. 535,702.

My invention relates to metal tiles of pre-selected dimensions intended to constitute the wear-receiving surface of a highway, drive or runway and adapted to be placed on a road surface at the time of construction to permit certain depending portions of the tile to embed themselves in the road surface so as to firmly anchor the metal tiles in place.

The object of my invention is to provide 10 a non-flexing tile provided with a traction providing surface, with the lower side of the tile provided with a plurality of anchoring portions which cause the tile to be held against movement; the tile being especially intended 15 for use on concrete roads or trucking runways where the latter are subjected to heavy wear so as to protect the concrete against disintegrating or destructive effect resulting from the frictional and pounding action of 20 passing traffic.

The objects and advantages of my invention will be readily comprehended from the detailed description of the accompanying drawings, wherein:

25 Figure 1 is a top plan view of my improved paving tile in position on a roadway; a complete tile being shown and portions of juxtaposed tiles being shown at opposite sides.

Figure 2 is a cross-sectional view taken 30 substantially on the line 2—2 of Figure 1, as viewed by the arrows.

Figure 3 is an inverted perspective view of a section of a tile taken along the line 3—3 of Figure 1 as viewed by the arrows with 35 the concrete omitted.

Figure 4 is a sectional view similar to Figure 2, illustrating a modified form of the paving tile.

40 Figure 5 is a plan view, similar to Figure 1, illustrating another modified form of my improved paving tile.

Figure 6 is a longitudinal sectional view taken substantially on the line 6—6 of Figure 5 as viewed by the arrows.

45 My improved paving tile is formed of suitable metal, either cast or pressed into shape; cast iron being preferably employed because of its non-rusting nature; and the tiles are preferably of polygonal form to permit the tiles to be arranged in close juxtaposition so

as to provide a continuous wear resisting surface for a preselected locality in the roadway.

The tiles are of any predetermined dimensions which will permit easy handling and are of a thickness so as to be wear resisting and afford full protection for the surface of the road or run-way. My improved metal tile is intended to be laid in place while the road surface is still in a more or less plastic 55 or yielding state; being especially intended for concrete roads or run-ways of cementitious material, on which it is laid and pressed into place before the cementitious material becomes "set"; and in the exemplification 60 shown in the first three figures of the drawings consists of suitable sized metal plates 10, having straight side edges and preferably 65 of the rectangular shape shown.

In Figure 1 I illustrate a complete tile 10, 70 with portions of tiles at each side and along the bottom of the figure. As all of these tiles are of similar construction and configuration a description of one tile will suffice.

The tile at its perimeter, namely along all 75 of its edges, is provided with a depending flange portion 11 provided with a straight vertical outer face, see Figure 2, so as to permit a flush abutting relation with the perimeters of the adjacent tiles. These flange portions 11, on their inner faces and adjacent to the lower marginal edges thereof, are formed with the laterally disposed enlargements 12 having top and bottom sides converging toward each other, so as to form anchoring portions, somewhat V-shape in cross-section on each tile, as more clearly shown in Figure 2.

Each tile 10, in addition to the marginal flanges described, are also provided with 90 transverse, intersecting depending ribs or portions 13, 13, which extend from side to side along the bottom of the tile and preferably unite at their ends with the marginal depending portions 11. The transversely disposed depending portions 13, 13, adjacent to their lower longitudinal edges, are enlarged laterally on opposite sides of the median lines thereof, as shown at 14 (see Figure 3), with the enlargements preferably provided with 95 100

sloping top and bottom sides, thereby forming anchoring portions somewhat diamond-shaped in cross-section.

With the marginal depending portions 11 and the transverse intersecting portions 13, 13 formed as shown and described, it is apparent that the tile may be pressed into place, as the pointed lower edges of these depending portions will permit said portions to be readily pressed into the plastic or unset concrete or soft material and the road material or concrete will enter the space between the enlarged heads 12, 14 and the lower side of the tile. It is apparent, when the concrete becomes "set" or hardens, that the tile will be immovably anchored in place and practically become an integral part of the roadway; while at the same time the marginal depending portions 11 will prevent lateral displacement of the moldable or cementitious material beyond the outer sides of the tiles at opposite sides of the roadway.

Each tile 10, in the form shown in Figures 1 to 3, are provided with symmetrically spaced relatively large openings at 15, preferably of the circular formation shown. These openings 15 are provided with sloping converging sides as shown at 16 in Figures 2 and 3 and the lower side of the tile around the openings is provided with depending encircling flanges 17 which initially are arranged in alignment with the sloping sides of the openings in the tile proper and the flanges 17 then disposed in the laterally diverging manner, at their lower ends, as shown at 18.

It is apparent that the plastic material or concrete of the roadway, which enters the tile when the latter is pressed into place, will not only form a binding relation with the tile because of the gradually increasing diameter of the hole toward the upper face of the tile, but a further anchoring effect is obtained by the unset concrete flowing into the chamfer or encircling socket on the lower side of the tile formed by the oppositely sloping flange portions 17 and 18.

The openings 15 are preferably intended to be completely filled with the sub-surface material or concrete from which the roadway is made, and therefore concrete may be poured into the openings 15 before the sub-surface has become "set" or hardened so as to bring the concrete flush with the top surface of the tile.

The tile, in addition to its anchorage by the depending portions 11 and 13, will be further securely held in place by the dual anchorage provided by the formation of the openings and the encircling flanges at the lower sides.

In Figure 4 I illustrate a slight modification of the tile shown in Figure 1, in so far as the opening encircling flange is concerned; the tile 10^a of Figure 4 it will be

understood is to be provided with the marginal depending headed flanges 11 and the transverse intersecting headed ribs or portions 13 on the bottom side of the tile like that heretofore described.

In the form shown in Figure 4, the tile 10^a is also provided at prearranged spaced points with relative large openings 15^a having converging sides and the lower side of the tile provided with the encircling flanges 19 arranged in keeping with the sloping converging sides of the openings in the main part of the tile. That is to say, the flanges 19 continue in a straight line or direction and are not of the angular formation shown in the preceding figures; the flanges 19 preferably tapering somewhat toward the bottom as shown. The openings, as previously stated, are to be filled with concrete before the under-pavement becomes set, thus, like in Figure 1, providing the comparatively deep concrete locking and integral wedge portions which, in addition to the marginal portions 11 and the transverse portions 13, will firmly anchor the tile to the subjacent material of the roadway.

In Figures 5 and 6, I illustrate another modified form of my improved tile; the tile 10^b being made without the sub-surface receiving openings of the tiles shown in Figures 1 and 4. The tile 10^b, like the previously described forms, being provided with the marginal flanges 11 having the laterally extending substantially V-shape head portions 12 and with the transverse intersecting depending rib portions 13 provided with the somewhat diamond shape or enlarged tapered head portions 14. The head portions 12 and 14 being arranged at a slight distance beneath the bottom face of the tile, permit the concrete or material from which the road is constructed to flow or enter the grooves formed above the head portions and as a result the tile will be firmly united with the roadway when the concrete or material hardens.

The top of the tiles are all preferably provided with traction providing surfaces consisting of series of pyramidal portions 20. Aside from affording traction, these pyramidal portions provide for increased strength in the tile and greater wearing quality.

I am aware that paving blocks of concrete with thin metal sheet coverings imbedded on the upper surfaces of the blocks and constituting an integral part of each block have been devised; as have also iron pavements, namely fabricated iron which constituted the paving material; and that reenforcing plates, put into place before a road paving has been laid, intermediate of railroad rails, have also been suggested.

My improved tile, however, which is of comparative thickness, is intended as the wear receiving surface of the road and there-

fore not in itself to constitute the main paving material; the tile being applied after the road has been constructed and laid and then to be pressed onto the road surface, with the 5 tile so formed that the sides may be arranged in close abutting relation to provide a continuous covering in places where heavy traffic is encountered, with each tile so formed that it will firmly anchor itself to the road pav- 10 ing.

What I claim is:

1. A metallic tile comprising a flat plate of polygonal shape, the perimeter of the plate having a continuous depending flange, while 15 the bottom of the plate is provided with transversely disposed intersecting flanges, with the inner face of the perimetric flange and said intersecting flanges adjacent their lower marginal edges having laterally disposed enlargements with oppositely beveled faces to provide a lower wedging surface and a locking upper surface adapted to be pressed into a roadway surface; the tile being pro- 20 vided with paving material receiving open- 25 ings having side walls converging toward

the bottom of the plate, and depending flanges on the plate bottom about said openings.

2. A metallic tile comprising a flat plate of preselected dimensions and shape, the perimeter of the plate having a continuous depending flange while the bottom of the plate is provided with transversely disposed intersecting flanges, all of the flanges adjacent their lower marginal edges being laterally enlarged and said enlargements having oppositely beveled faces to provide a lower wedging surface and an upper locking surface adapted to be pressed into a roadway surface; the plate being provided with paving material receiving openings of comparative size having side walls converging toward the bottom of the plate, said openings being surrounded by depending flanges with the lower ends of the flanges being disposed in a direction reverse to that of the upper parts of the flanges whereby the plates are locked in the sub-surface.
